UNITED STATES PATENT OFFICE.

HENRY L. HASKELL, OF LUDINGTON, MICHIGAN.

DESIGN FOR A GAME-TABLE.

SPECIFICATION forming part of Design No. 33,437, dated October 23, 1900.

Application filed January 16, 1900. Serial No. 1,695. Term of patent 14 years.

To all whom it may concern:

Be it known that I, HENRY L. HASKELL, a citizen of the United States, residing at Ludington, in the county of Mason and State of Michigan, have invented a certain new and original Design for Game-Tables; and I do hereby declare the following to be a full, clear, and exact description of the invention, such as will enable others skilled in the art to which it appertains to make and use the same.

The design herein illustrated is for a game-table to be used, for example, to hold a game-board which it is necessary or desirable to revolve in the course of use.

The distinguishing features of the design are the relation of the arms which carry the board to the legs and blocks which support the arms and the conformation of the arms and the legs and blocks.

In the drawing the figure is a view in perspective of the table.

The arms are indicated by 1, the point of joining by 2, cushions by 3, legs by 4, and blocks joining the legs by 5.

6 represents base-cushions or supports for the legs.

In this illustration the table is shown open and ready for use.

What I claim is—

The design for a game-table substantially as shown and described.

In testimony whereof I have hereunto set my hand in presence of two subscribing witnesses.

HENRY L. HASKELL.
